UNITED STATES PATENT OFFICE

139,205

DESIGN FOR A FLAG

Harry J. Tompkins, Pasadena, Calif., assignor to Wendell L. Wilkie, New York, N. Y.

Application March 21, 1944, Serial No. 112,980

Term of patent 7 years

(Cl. D29—17)

To all whom it may concern:

Be it known that I, Harry J. Tompkins, a citizen of the United States, residing at Pasadena, in the county of Los Angeles and State of California, have invented a new, original, and ornamental Design for a Flag, of which the following is a specification, reference being had to the accompanying drawing forming a part thereof.

Fig. 1 is a plan view of a flag showing my new design, the drawing being lined to show different contrasting colors; and

Fig. 2 is an end elevational view of the flag shown in my design.

I claim:

The ornamental design for a flag, as shown and described.

HARRY J. TOMPKINS.
